UNITED STATES PATENT OFFICE

147,482

DESIGN FOR A CHEST OR THE LIKE

Henry Winterfeld, New York, N. Y.

Application May 3, 1946, Serial No. 129,260

Term of patent 7 years

(Cl. D33—19)

To all whom it may concern:

Be it known that I, Henry Winterfeld, a citizen of the United States, residing at New York, in the county of New York and State of New York, have invented a new, original, and ornamental Design for a Chest or the like, of which the following is a specification, reference being had to the accompanying drawing, forming part thereof.

In the drawing

Fig. 1 is a perspective view of my new design relating to a chest or the like, showing the same in open position.

Fig. 2 is a top view thereof in closed position.

Fig. 3 is a side view thereof in closed position, and

Fig. 4 is a front view thereof in closed position.

I claim:

The ornamental design for a chest or the like, as shown.

HENRY WINTERFELD.
